PLAITING MACHINE

Holton M. Sutherland, Swampscott, Mass., assignor to Boston Machine Works Company, Lynn, Mass., a corporation of Massachusetts

Application March 14, 1939, Serial No. 261,736

11 Claims.

(Cl. 12—51)

The present invention relates to machines which are used in the manufacture of shoes to plait various shoe upper blanks.

The prevailing style trend requires shoes to be 5 ornamented by a large number of plaits, and the shoe industry is embarrassed by its inability to produce them economically. For instance, in order to make a plaited shoe, it has been the common practise to mark the upper blank to be 10 plaited with inked lines, which the operative uses as guides in forming the plaits by hand, the creases of the plaits when formed coinciding as near as may be with the inked lines.

The principal object of the present invention is 15 to make a plaiting machine by which the upper blank may be plaited in a rapid, reliable and economic manner.

To the accomplishment of this object, and such others as may appear hereinafter, the various 20 features of the present invention reside in certain constructions and arrangements of parts hereinafter described and then set forth broadly and in detail in the appended claims which possess advantages readily understood by those 25 skilled in the art.

The various features of the present invention will be readily understood from an inspection of the accompanying drawings, in which,

Figure 1 is a detail view in left-side elevation 30 of the machine;

Fig. 2 is a detail view in front elevation;

Fig. 3 is a detail view in perspective showing the relationship between the work support, the piece of sheet material thereon, the hammer for 35 pounding the plait, and the plaiting fingers;

Fig. 4 is a detail view in left-side elevation illustrating the position of the hammer near the end of the first half of its idle stroke;

Fig. 5 is a similar detail view illustrating the 40 position of the hammer near the end of the second half of its idle stroke;

Fig. 6 is a similar detail view illustrating the position of the hammer on its active stroke;

Fig. 7 is a similar detail view illustrating the 45 position of the hammer on the first quarter of its idle stroke;

Fig. 8 is a detail view in plan illustrating the finished or grain face of the plaited work, and

Fig. 9 is an enlarged view in sectional elevation 50 of the unfinished or flesh face of the plaited work on the line 9—9, Fig. 8.

In the illustrated embodiment of the invention, the piece of sheet material 10 is supported upon a roll work support 11 which is mounted 55 in a vertical slot 12 formed in a yoke 13. The yoke carries a horizontal pin 14 upon which the roll is rotatably mounted. The yoke 13 slides vertically in a hollow pedestal 15 secured to the frame of the machine. The vertical movement of 60 the yoke 13 is guided by a cylindrical extension 16

thereon which slides in the bore of the pedestal, a pin 17 projecting rearwardly from the extension being engaged by a vertical slot 18 in the pedestal. The roll 11 is normally held elevated by a coiled spring 19 which is coiled about a post 5 20 depending from the extension 16 and interposed therebetween and a plug 21 threaded into the bore of the pedestal 15 at the lower end thereof. The roll 11 may be depressed against the tension of the spring 19 by suitable connections from a treadle-operated rod 22. The pin 17, in conjunction with the slot 18, serves the double function of keeping the roll in its proper alignment with the hammer 23 and the work 10, and at the same time limiting the upward movement 15 of the roll 11 by the spring 19.

Cooperating with the roll 11 is a hammer 23 having its work engaging face 24 roughened laterally and provided with a relief 25, (Fig. 3), in the line of feed. The hammer 23 may be 20 formed upon the end of a rod 26 which is adjustably mounted in one end of a lever 27, the upper end of which has a strap and link connection with an eccentric 28 on the power-driven shaft 29. The lever 27 is provided with a slot 30, 25 the vertical sides of which engage the grooved sides of a block 30a which is pivotally mounted on a horizontal pin 31 projecting laterally from the machine frame. With this construction, the lever 27 is reciprocated on the block 30a and is 30 oscillated on the pin 31, thus imparting a combined reciprocating and oscillating movement to the hammer.

In order to plait the work, the machine is provided with two fingers 32 and 33 arranged to engage the opposite faces of the work, respectively. The finger 32 is formed with a narrow portion terminating in a toe 34 and a wide portion terminating in a heel 35. The heel 35 is secured 35 to a slide 36 which is adjustably mounted in a 40 way 37, (Fig. 3), formed in a block 38 supported from the pedestal 15. The desired position of vertical adjustment of the finger 32 is maintained by a set screw 39 threaded into the block 38, the shank of the screw being embraced by a vertical 45 slot 40 in the slide 36. The block 38 is provided with a lower portion 48 threaded into the pedestal 15 and secured by a lock nut 49, the construction permitting the lateral adjustment of 50 the finger 32.

The finger 33 is provided, also, with a narrow portion terminating in a toe 41 and with a wide portion terminating in a heel 42. The heel 42 is carried by a plate on the lower end of a rod 44 which is vertically and angularly adjustable in a 55 yoked bracket 45 secured to the machine frame, the desired position of vertical and angular adjustment being maintained by a set screw 46 engaged with the upper portion of the rod 44.

As shown most clearly in Fig. 3, the heels of 60

the fingers 32 and 33 are spaced apart laterally and vertically, the heel 42 of the finger 33 being higher than the heel 35 of the finger 32, while the toes thereof are superimposed and spaced 5 apart vertically, the adjacent sides of the fingers being arranged in parallel intersecting vertical planes. The toe 34 of the finger 32 toes slightly inwardly and upwardly. The toe 41 of the finger 33 toes inwardly and downwardly. With 10 this construction, the toe of the finger 32 is located above the toe of the finger 33.

To plait the work, the piece of sheet material is first marked with guide lines and then, in the area to be plaited, it is provided with an adhesive 15 coating. The operative grasps the side edges of the piece 10 and introduces it between the V form by the heels of the fingers 32 and 33 in a position more horizontal than vertical. The piece is then pushed forwardly to locate the work between the toes of the fingers, thus to engage the toe 41 of the finger 33 with the unfinished or flesh face of the work and the toe 34 of the finger 32 with the finished or grain face of the work, thereby making it possible for the hammer to engage 20 the flesh face of the work.

As shown in Fig. 3, the work is passed over the toe 34, in between the toes, and under the toe 41, thus to form a plait 47 before the leading edge of the work is located upon the work support beneath the hammer. The hammer then pounds the plait to flatten it and to subject the adhesive faces of the plait to pressure. During 30 its active stroke, the hammer feeds the work and then returns on its idle stroke to impart a blow to the succeeding portion of the plaited work. During the idle stroke of the hammer, the operative may swing the work laterally about the toes of the fingers, in order to produce a curvilinear plait, as indicated in Fig. 8.

40 The plaiting operation is repeated for each plait the sheet of material is intended to contain.

Nothing herein explained is to be interpreted as limiting the various features of the present invention in the scope of its application to use in connection with the particular machine or the particular mode of operation or both selected for purposes of illustration and explanation. While the particulars of construction herein set forth are well suited to one mechanical form of the invention and to the use to which it is put, it is not limited to this use, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

60 What is claimed as new, is:

1. A plaiting machine having, in combination, means for supporting a piece of sheet material, means cooperating therewith for pounding a plait produced in the material in spaced relation to the side edges thereof, and means for producing the plait while the side edges of the material are grasped by the operative.

2. A plaiting machine having, in combination, a work support for supporting a piece of sheet material, a hammer cooperating therewith for

pounding a plait produced in the material in spaced relation to the side edges thereof, and means, mounted in advance of the work support, and through which the sheet material is forced to locate the leading edge of the material upon the work support while the side edges of the material are grasped by the operative for producing the plait.

3. A plaiting machine having, in combination, a work support for supporting a piece of sheet material, a hammer cooperating therewith for pounding a curvilinear plait produced in the material in spaced relation to the side edges thereof, and means, mounted in advance of the work support, and through which the sheet material is forced longitudinally and swung laterally while the side edges of the material are grasped by the operative, to locate the leading edge of the material upon the work support, for producing the curvilinear plait.

4. A plaiting machine having, in combination, a work support, a pair of cooperating fingers for forming a plait in the work, and a hammer cooperating with the work support to pound the plait.

5. A plaiting machine having, in combination, a work support, a pair of cooperating fingers for forming a plait in the work, and a hammer cooperating with the work support to pound the plait and to draw the work through the fingers.

6. A plaiting machine having, in combination, a work support, a pair of cooperating fingers for forming a plait in the work, and a hammer cooperating with the work support to pound the plait, to draw the work through the fingers and to feed the plaited work over the work support.

7. A plaiting machine having, in combination, a work support, a pair of cooperating fingers having their heels spaced laterally and their toes spaced vertically, engaged, respectively, with the opposite faces of the work, and means cooperating with the work support for drawing the work through the fingers.

8. A plaiting machine having, in combination, a work support and a pair of work engaging cooperating fingers separate therefrom having their work engaging surfaces elevated one above the other and their adjacent side faces arranged substantially in intersecting vertical planes.

9. A plaiting machine having, in combination, a work support and a pair of work engaging cooperating fingers separate therefrom having the toes thereof superimposed and spaced vertically and engaged, respectively, with the opposite faces of the work.

10. A plaiting machine having, in combination, a work support and a pair of work engaging cooperating fingers separate therefrom having the toes thereof superimposed and spaced vertically and engaged, respectively, with the opposite faces of the work, and about which toes the work may be swung laterally as the work is fed longitudinally therebetween.

11. A plaiting machine having, in combination, a work support and a pair of plaiting cooperating fingers separate therefrom having the toes thereof superimposed and spaced vertically and engaged, respectively, with the opposite faces of the work, and means for varying the lateral relationship of the toes of the fingers.

HOLTON M. SUTHERLAND.
